CLOTH HANDLING APPARATUS

Clarence T. Graham, North Attleboro, Mass., assignor to Defiance Manufacturing Company, Barrowsville, Mass., a corporation of Massachusetts

Application May 19, 1944, Serial No. 536,347

2 Claims. (Cl. 68—178)

1

The present invention relates to an improvement in cloth handling apparatus such, for example, as pilers of the type having a portion commonly known as the "J" box.

In cloth finishing and analogous operations carried out in a continuous process, it is desirable that all parts of the mass, as of cloth raw stock, be moved into and through the various treating steps without interruption so as to secure uniformity of result throughout the piece or pieces thus treated. Among various devices designed to aid in this respect is the "J" box piler, usually a chute having a vertically arranged receiving end and an upwardly curved discharge end. One difficulty experienced in the use of "J" boxes of this type has been that, in starting, as the web or "rope" of cloth feeds into the receiving end, the material is tumbled and tangled into a loose uncontrolled mass until the piler fills solid and the flow or movement of the material therethrough becomes normal, i. e. until the amount removed from the discharge end of the filled up piler is substantially at the same rate as the amount fed in at the receiving end.

One object of the present invention has been to provide a device for controlling the movement and placing of cloth in a piler or the like wherein the starting operation may be so controlled that the material is initially received in the piler with no tangling or undue tumbling about. A further object has been to provide a "J" box whereby the cloth or other material is accumulated and compacted in an ordered mass so that when the leading end of the "rope" of cloth reaches the discharge end of the piler, the material may be drawn off promptly and effectively with no snarls or tangles to interrupt the operation.

One embodiment of my invention is described in the following specification and illustrated in the drawings appended thereto and in which—

Figure 1 is a view in central longitudinal vertical section, with a part shown in side elevation;

Figure 2, a top plan view; and

Figure 3, a transverse vertical section on the line 3—3 of Figure 1.

Referring to the drawings, a piler according to my invention and as applied to a "J" box has a receiving end portion in the form of an upright chute 1 and a discharge end portion in the form of an upright chute 2. A curved passageway or chute portion 3 connects the upright chutes 1 and 2. The bottom wall of curved chute 3 is made up of a series of rollers 4 journaled in the opposed side walls 5.

A portion of the top wall of curved chute 3 is

cut away to provide an opening 12 into or through which a gate 6 may be swung in operating the device.

Said gate 6 is secured to a shaft 7 and is mounted at one edge of opening 12 to swing to and from a position across the inside opening of a lower end portion of inlet chute 1, or between said chute 1 and curved chute 3. To control operation of said gate 6, a pinion 8 on shaft 7 engages and is rotated by a screw 9 operated by handle 10.

In use, the gate 6 or other equivalent baffle or barrier member is initially brought to the operative chute closing or cloth receiving position, as shown in full lines, Figure 1 for example. The cloth or other material to be piled is fed into chute 1, often in the form of a "rope," in a manner to deposit the leading end on gate 6 and to pile succeeding increments up in regular manner thereon. When a suitable mass of material so placed or distributed has accumulated in chute 1, or when the latter is full, gate 6 is swung downwardly, or toward opening 12 to free the compacted mass of material for movement into curved chute 3. Under some circumstances it will be desirable to swing gate 6 quickly to full open position (dotted Fig. 1). Under other conditions the movement may be slower, or the gate may be swung to an intermediate position. In the latter case, it may operate as a brake to control the rate of movement of the accumulated mass of material into the curved chute 3 and thence into the discharge chute 2.

In any case, the piled material accumulated as above described on the gate or barrier 6 is moved into and through the piler with no tangling or distortion, and therefore with no delay or interruption due to such conditions.

It is contemplated that a cloth movement controlling device according to my invention may be effectively used in a wide variety of cloth handling operations such as occur in the textile and allied trades and involve the use of piling machines, bins, chutes, kiers, bleaching machines and similar devices.

I claim:

1. In a cloth handling apparatus comprising an upright cloth receiving chute and an upright cloth discharge chute, the combination of a curved chute having top, sides and bottom walls and arranged and adapted to connect said upright chutes and to provide a passageway for the movement of cloth from said receiving chute to said discharge chute, said curved chute having an opening in said top wall, a gate swingably mount-

ed at the upper edge of said opening and having a tendency to swing across said curved chute under the action of gravity and being substantially coextensive in area with the area of the opening, and manually controlled means arranged and adapted to move said gate in one direction toward operative position between said receiving chute and said curved chute and in the opposite direction to such position that it will close said opening in said wall of said curved chute and will be located out of the path of travel of the cloth through said curved chute.

2. In a cloth handling apparatus comprising an upright cloth receiving chute and an upright cloth discharge chute, the combination of a 15 curved chute having top, sides and bottom walls and arranged and adapted to connect said upright chutes and to provide a passageway for the movement of cloth from said receiving chute to said discharge chute, said curved chute having an opening in said top wall, a gate swingably mounted at the upper edge of said opening and having a tendency to swing across said curved chute under the action of gravity and being substantially coextensive in area with the area of 20 the opening, and manually controlled means ar-

ranged and adapted to move said gate in one direction toward operative position between said receiving chute and said curved chute and in the opposite direction to such position that it will close said opening in said wall of said curved chute and will be located out of the path of travel of the cloth through said curved chute, said manually controlled means including a pinion on said gate and an interengaging screw on said receiving chute constructed and arranged to maintain said gate in position to close said opening against the action of gravity and to maintain said gate in position across said curved chute.
